UNITED STATES PATENT OFFICE.

KARL HUGO MORÉN, OF BOFORS, SWEDEN.

SHELL-FUSE.

1,216,834.

Specification of Letters Patent. Patented Feb. 20, 1917.

Application filed July 18, 1916. Serial No. 109,864.

To all whom it may concern:

Be it known that I, KARL HUGO MORÉN, a subject of the King of Sweden, residing at Bofors, Sweden, have invented new and useful Improvements in Shell-Fuses, of which the following is a specification.

My invention has for its object a means for keeping the detonator and the detonating charge in shell fuses separated from each other until the projectile has left the muzzle of the gun. According to the invention a conical spring actuated cover on the detonating charge is kept in safe position by means of one or more balls, which are situated in openings in an annular member and rest against the surrounding wall of the fuse body. When the annular member at the firing is released from its safe or locked position the compressed spring forces the said member with the balls and the cover of the detonating charge forward until the balls pass a recess in the wall of the fuse body, whereby they are pressed outward by the conical cover, while the detonating charge still is forced forward by the spring.

In the accompanying drawing a shell fuse arranged according to this invention is illustrated in a longitudinal section.

1 is the fuse body, the front end of which contains the usual percussion mechanism with powder channels, 2 is the detonator, which is introduced in a corresponding recess 3 of the detonating charge 4, when the projectile shall be used, but during transport or storing is kept separated from the said charge, which thus cannot be unintentionally ignited. According to my invention the detonator and the detonating charge are kept separated from one another by means of an annular safety member 5, surrounding the detonator, in which member enters a cover 7 for the detonating charge 4. This cover is acted upon by a spring 6 forcing it forward and is held by means of one or more balls 9, placed in openings 8 in the annular member 5 and resting against the wall of the surrounding

fuse body 1. The inner portions of these balls project in the path of the cover 7 and prevent it as well as the detonating charge from passing forward over the detonator, when the member 5 is held in its safe position, for instance by means of a piston 10 and a powder pill 11 which is burnt at the firing. When the member 5 is released from the safe position, it will together with the other parts acted upon by the spring 6 (the balls 9, the cover 7 and the detonating charge 4) be forced forward until the balls pass a recess 13 in the wall of the fuse body, in which they are forced by means of the moving conical cover. When the balls in this manner are brought out of the way of the cover the detonating charge independent from the member 5 can be pushed forward over the detonator 2 by the spring 6.

Having now particularly described the nature of my invention and the manner of its operation, what I claim is:

In a fuse for shells, a hollow body, a detonating charge container slidably disposed within said body and provided with a cover having a beveled forward edge, a safety member having a longitudinal passage large enough to receive said container, disposed forwardly of said container, a spring tending to force said container into said passage, balls disposed between said member and the beveled edge of the container and bearing against the inner surface of the fuse body to prevent movement of the container, the said fuse body being provided with a recess to receive said balls on forward motion of the safety member, means for retaining said safety member in safe position, and means for releasing said safety member as the shell is fired.

In testimony whereof I have signed my name to this specification in the presence of two subscribing witnesses.

KARL HUGO MORÉN.
